INSULATED ROOF AND WALL COVERING

William W. Westphal, Port Jefferson, N. Y.

Application November 25, 1949, Serial No. 129,292

4 Claims. (Cl. 20—4)

1

This invention relates to a novel combination covering and insulating unit for roofs and walls adapted to be applied over existing shingles or siding as an under cover for a composition shingle or siding to be applied thereover.

In applying composition shingles or siding of either asphalt or asbestos or the like to existing roofs or wooden walls or to new structures, it is a practice to initially cover the roof or siding with heavy felt paper and where the shingle roof or siding is stepped to first apply strips of substantially wedge shaped cross section in the recesses of the roof or siding to provide a substantially smooth and flat surface over which the felt paper is applied. These beveled filler strips which are formed of wood must be nailed in place after which the felt paper must either be nailed to the roof or siding with large headed nails or held by retaining strips which are nailed to the roof or siding. The wood filler strips afford a space which is readily accessible to termites and if any seepage of water occurs to dampen such strips it is quite common for the strips to buckle and injure or displace the composition shingles or siding which is applied thereover. Furthermore, the felt paper is heavy and difficult to handle and if a rain occurs before the composition shingles or siding can be applied thereover, it is ordinarily necessary to replace the paper.

Accordingly, it is a primary object of the present invention to provide a covering to be applied beneath composition shingles or siding which will eliminate the use of the beveled filler strips and felt paper and which will additionally insulate and fur the roof or wall and which is not accomplished by the felt paper and beveled filler strips.

Still another aim of the invention is to provide a combination insulating covering unit for roofs and walls capable of being very conveniently handled and quickly and easily applied to a roof or wall and which is capable of withstanding without damage a heavy rain before composition shingles or siding are applied thereover.

Various other objects and advantages of the invention will hereinafter become more fully apparent from the following description of the drawing, illustrating a presently preferred embodiment thereof, and wherein:

Figure 1 is a fragmentary end elevational view, partly broken away and partly in section illustrating the invention applied to a roof and wall of a building;

Figure 2 is a vertical sectional view taken substantially along a plane as indicated by the line 2—2 of Figure 1;

Figure 3 is an enlarged vertical sectional view taken substantially along a plane as indicated by the line 3—3 of Figure 1;

Figure 4 is an enlarged fragmentary perspective view showing several of the roof or wall cov-

2

ering units as they would appear when assembled together in a course;

Figure 5 is a plan view, partly in section looking toward the inner side of one of the covering units and on a reduced scale, and

Figure 6 is a perspective view looking toward the inner side of said covering unit and with the insulating filler thereof removed.

Referring more specifically to the drawing, the novel roof or wall covering unit in its entirety and which comprises the invention is illustrated in Figure 5 and designated generally 7 and includes a piece of heavy felt paper, designated generally 8 of the type usually employed for covering a roof or wall beneath the composition shingle or siding and which includes an elongated strip designated generally 9 and an extension 10 which forms a lateral extension of the upper edge 11 of the strip 9. As clearly illustrated in Figures 5 and 6, the extension 10 terminates short of the ends of the strip 9 and is adapted to be folded over and overlie a portion of one side of the strip 9, as illustrated in Figure 6.

The extension 10 is secured to the said side of the strip 9 by a filler 12 of insulating material which may be formed of sawdust, rock wool or wood fiber which is bonded together by a suitable binder such as asphalt and which is molded so as to be substantially wedge shaped in cross section,

as best illustrated in Figures 3 and 4. The widest longitudinal edge of the insulating filler 12 is disposed adjacent the upper edge 11 of the strip 9 so that the extension 10 extends outwardly from said edge 11 at substantially a right angle to the strip 9 and then extends downwardly and in converging relationship to the strip 9. As previously stated, the ends of the extension 10 are spaced from the ends of the strip 9 so that the end portions of said strip 9 form end flaps 13 and the free edge of the extension 10 is spaced from the bottom edge of the strip 9 so that the portion of the strip 9, located below the extension 10 and filler 12 forms a bottom flap 14.

The roof and wall covering and insulating unit 7 may be made in various lengths and widths to be conveniently handled and packed in bundles and are adapted to be used primarily in applying composition roofing shingles over an existing shingle roof or in connection with applying composition siding over an existing stepped siding of a building, as illustrated in Figures 1, 2 and 3 and wherein a portion of such a side wall 15 and such a roof 16 of a wooden building, designated generally 17 is illustrated. The application of the covering and insulating unit 7 to the wall and roof are exactly the same and accordingly will only be described in connection with the wall 15. As illustrated in Figures 2 and 3, the siding members 18 of the wall 15 are ordinarily formed of wood and are stepped so that each of the siding

members 18 is substantially wedge shaped in cross section and with its bottom edge constituting its widest edge and its upper edge constituting its narrowest edge. The covering and insulating unit 7 are applied in courses starting at the bottom and working toward the top of either a wall or roof and the filler portion 12 of each unit 7 is of substantially the same width as the exposed surface of one of the siding members 18 or one of the roof shingles. In the bottommost course of unit 7, the bottom flaps 14 may be cut off or folded under and the end flaps 13 adjacent each end of the wall and of all the courses of the units 7 may likewise be cut off or folded under. Each unit 7 may be secured to the wall or roof by approximately three spaced driven fastenings 19 which are driven through the pad or filler 12 near its wider, upper edge. The units 7 are applied, as best illustrated in Figure 3, with the sides of the strips 9 on which the fillers 12 are disposed positioned innermost or against the siding members 18 and the adjacent units 7 of each course are disposed with the ends of the pads in substantially abutting engagement, as best illustrated in Figure 4. This is accomplished by folding one end flap 13 across the end of the filler or pad 12 of its unit 7 and then extending it so that it will lie beneath the adjacent end of the adjacent pad or filler 12 while the other adjacently disposed end flap 13 is extended to overlie the outer side of the strip 9 of the adjacent unit 7, all as clearly illustrated in Figure 4. The successive courses may be disposed in staggered relationship, as illustrated in Figure 1 and as seen in Figure 3, the widest portion of each pad or filler 12 is of a sufficient width preferably to extend slightly outwardly from the widest part of the siding member 18 disposed thereabove and so that the narrow bottom edge of the filler 12 of the unit 7 disposed thereabove may abut thereagainst. In each of the courses of units 7, above the lowermost course, the bottom flaps 14 will extend downwardly to overlie the upper portion of the units 7 of the course disposed directly therebeneath and so as to cover the driven fastenings 19 by which said lower course is secured to the wall 15 or roof 16.

Accordingly, it will be readily apparent that the entire wall or roof surface is covered by the fillers 12 of insulating material and by two plies of the felt paper 8, as illustrated in Figure 3, so that the wall 15 or roof 16 will be insulated against heat or cold and will be adequately protected by the two spaced felt paper coverings 9 and 10. After the wall 15 or roof 16 has thus been covered completely with the courses of the units 7 the siding members 20 or shingles 21 are applied thereover and secured in any conventional manner by driven fastenings 22, which may be arranged, if desired, so that the fastenings will be covered by the overlaps of the siding members or shingles. It will be noted that the pads or fillers 12 will also space the shingles 21 or siding members 20 from the roof 16 or wall 15, respectively, to thereby function additionally as furring members.

Various modifications and changes are contemplated and may obviously be resorted to, without departing from the spirit or scope of the invention as hereinafter defined by the appended claims.

I claim as my invention:

1. The combination with a roof, of an insulating covering applied to the exterior of the roof beneath composition shingles, comprising a plu-

ality of corresponding covering units forming the insulated covering each consisting of a strip of felt paper and a filler of insulating material, said strip of felt paper having an upper edge provided with an integral extension overlying a portion of one side of said strip, said filler being disposed between said strip portion and the extension thereof and including an adhesive binder for anchoring said extension in overlying relationship to the strip portion, said strip having end portions and a bottom edge portion extending beyond the ends and below the bottom edge, respectively, of said filler forming end flaps and a bottom flap, said covering units being arranged in courses to form the insulated covering and said end flaps of each covering unit overlapping portions of adjacent covering units disposed in the same course, the adjacent ends of the fillers of adjacent covering units of each course being disposed substantially in abutting engagement, and said bottom flaps of the covering units of each course overlying the upper portions of the covering units of a course located directly therebeneath.

25 2. An insulated covering as in claim 1, each of said fillers being wedge-shaped in cross section and tapered in thickness from its upper to its lower edge and filling a step in a shingle of the roof.

30 3. The combination with a siding wall and siding strips of composition material applied to the outer side thereof, of an insulating covering secured to the siding wall and disposed between the wall and the siding strips, comprising a plurality of corresponding covering units, forming the insulated covering, each consisting of a strip of felt paper and a filler of insulating material, said strip of felt paper being folded to provide inner and outer plies between which said filler is disposed, said filler including an adhesive binder for anchoring the filler to the felt paper plies and for positioning it therebetween, said paper strip including an outer ply having end portions extending beyond the ends of the filler and forming end flaps and a bottom portion extending below a bottom edge of said filler and forming a bottom flap, said covering units being arranged in courses to form the insulated covering and said end flaps of each covering unit overlapping portions of adjacent covering units disposed in the same course, the adjacent ends of the fillers of adjacent covering units of each course being disposed substantially in abutting engagement, and said bottom flaps of the covering units of each course overlying the upper portions of covering units of a course located directly therebeneath.

35 4. An insulated covering as in claim 3, said fillers being of wedge-shaped cross section and tapered in thickness from their upper to their lower edges and filling recesses of the siding wall.

WILLIAM W. WESTPHAL.
